UNITED STATES PATENT OFFICE

2,029,860

REFRIGERATOR DISPLAY CASE

Roland P. Daemicke, Chicago, Ill., assignor to The
Daemicke Company, Chicago, Ill., a corpora-
tion of Illinois

Application May 5, 1934, Serial No. 724,091

3 Claims. (Cl. 62—89.5)

My invention relates to service counters or cases of the mechanically refrigerated type for the display of perishable articles of food, such as meats and the like, wherein the refrigerating coils are preferably arranged in the bottom of the case and embedded in a suitable cold conducting slab forming compound or cementitious material.

My invention involves the idea of also embedding the refrigerating coil, which is disposed along the rear side of the case in a plane above the main bottom of the display case, in a slab of suitable material whereby dehydration of the display case contents and frosting of said coil, heretofore left exposed, will be prevented and the dripping of condensate onto the foodstuffs will also be prevented. This slab may be made of suitable cold conducting and more or less temperature retaining composition of stone particles or metal filings with a binder of plastic or cementitious material; and the slab may be made integral with a similar slab arranged to embed the coils of the display compartment bottom.

In display cases of this character, wherein the refrigerant medium containing coils are embedded as stated, it is necessary to employ wire or enameled trays for holding the cuts of meat instead of placing the meat directly on the bottom slab because it was found that the meat would become frozen to the slab and hence prevent its easy removal.

The use of the wire or enameled trays, however, has been found objectionable because proper air circulation and hence radiation of the cold air about the meat or other food-stuffs was interfered with.

Then, too, the use of trays not only necessitated the extra expense or cost of such trays, but also required the removal of the trays when proper cleaning of the display case was desired.

Another object of my invention is the provision of a construction whereby a more sanitary case is provided and the use of trays eliminated; the construction being such that direct contact with the coldest portions of the case bottom forming element is prevented and free flow of refrigerating air about the superposed meat or food-stuffs is obtained and hence a more uniform refrigeration provided.

The objects and advantages enumerated as well as other advantages inherent in the invention will all be readily comprehended from the detailed description of the accompanying drawing, wherein:

Figure 1 is an isometric sectional view of a display case provided with my invention.

Figure 2 is a detail sectional view of a bottom plate taken substantially on the line 2—2 of Figure 1 looking in the direction of the arrows.

My invention relates to mechanically refrigerated display cases especially intended for displaying meats and other food-stuffs which, upon selection by the customer, are to be removed from the case through suitable slide panels or doors. In this type of display case, the refrigerating coils, indicated at 10 in the drawing, have been embedded in a cementitious or other suitable cold temperature conducting material as indicated at 11; while the horizontally disposed pipe 10^a, arranged in a plane above the bottom, was left exposed.

This conducting material was usually arranged on top of a layer of insulating material as at 12. The compound or layer of conducting material 11 preferably consists of a mass of crushed stone or other conducting material mixed in or bound together by a suitable plastic material or binder, such as asphalt; or the conducting layer may consist of hydraulically setting cementitious material.

The mass 11 is preferably of a suitable thickness to completely encase the coils 10, except the immediate upper surfaces thereof; the top of the layer and across the upper surfaces of the coils 10 preferably consisting of a comparatively thin layer of the plastic binding material—such as asphalt for example.

In display cases adapted to mechanical refrigeration, it has been usual to leave the elevated coil, namely pipe 10^a, uncovered, causing considerable dehydration and frosting. One object of my invention is to also embed this coil or pipe 10^a in a temperature conducting and retaining compound 11^a which may be similar to and made continuous with the mass or material 11 of the bottom proper. The mass or slab which embeds pipe 10^a is formed so as to completely encase the pipe 10^a except at the forward side disposed toward the case interior. The outer surface of this slab or mass 11^a, like mass 11, consists of or is provided with a thin layer of the binding material. Before this layer becomes dry or "set" I place a metallic plate 13 thereon, preferably a metal, such as stainless steel, which will readily transfer the cold.

The plate is firmly pressed down onto the plastic binding material so as not to leave a space therebeneath, and when the plastic coating becomes

dry or "set" the plate 13 will be firmly sealed in place.

The plate 13, which is preferably coextensive with the bottom of the case and formed or bent 5 upwardly so as to extend across the front face of the slab portion 11^a, consists preferably of sheet metal which, throughout the main bottom forming portion, is formed to provide a plurality of upstanding arcuate portions or ribs 14. 10 These upstanding arcuate portions or ribs 14 are preferably formed to extend transversely of the sheet, namely in a direction transversely of the case from front to rear; the glass panel 15 constituting the front of the case, while the slide 15 panels or doors 16 are at the rear or salesman's side of the case.

The arcuate portions or ribs are uniformly spaced apart a predetermined distance and are of uniform height as shown, with the distance between 20 the adjacent ribs preferably somewhat greater than the height of the ribs; while the ends of these ribs terminate at a distance removed from the front longitudinal edge of the sheet and from the forward face of the slab portion 11^a, where the ribs slope downwardly or vanish into the plain or flat surface of the sheet, as shown at 17.

The metal sheet 13, at its forward longitudinal edge, namely beyond the forward ends of the ribs 14 and forward of the main portion of the slab material 11, is bent or dished to provide a drain 30 trough or gutter as at 18, whereby all moisture or water will be collected and conveyed to a suitable drain outlet at one end of the case.

When the sheet 13 is pressed downwardly onto the binding plastic material, a portion of the material displaced finds its way into the valleys or cavities on the lower side of the sheet formed by the upstanding arcuate portions or ribs 14, thereby 35 providing a thin coating on the lower sides of these ribs.

On the other hand, the main portion at the rear longitudinal side and the intermediate flat portions of the plate will practically contact with 45 the cooling coils 10 and coil 10^a; said portions being also in intimate contact with the cold conducting material or slabs 11 and 11^a in which the coils are embedded.

With the upstanding portions or ribs uniformly 50 spaced comparatively short distances apart, the need for trays as heretofore employed is obviated, as the cuts of meat or other food-stuffs may be placed directly on the ribs 13 of the plate.

By forming the upstanding portions or ribs 14 55 as described and shown, it is apparent that a series of open-ended air circulating channels are provided intermediate of the ribs, whereby proper circulation beneath the cuts of meat or other food-stuffs will be provided and the latter maintained 60 in better condition.

With my improved plate the cuts of meat cannot become frozen to the bottom chilling slab of the counter, as, however, has heretofore been the case, because of the somewhat insulated condition 65 of the ribs as heretofore mentioned, and hence the need of wire trays is obviated and the consequent expense eliminated.

Furthermore, with my improved construction, 70 a better and more economical refrigerated condition of the meats or food-stuffs is obtained, because the meats will be in direct contact with the outer cover of the cold conducting or chilling slab of which my improved plate becomes an intimate 75 part; the plate providing for direct radi-

ation from between the upstanding portions or ribs and from the rib sides.

A free flow of refrigerating air—namely air in immediate contact with the refrigerating slab or element—beneath the meat and other food-stuffs and in immediate contact therewith is also provided and constantly ensured; a condition, however, which is not obtainable with the trays as at present employed in display counters or cases of the class here in question. My construction, therefore, eliminates the expense of the usual trays; a more sanitary and slightly condition obtained and a more practical and easily cleaned display case bottom provided through the elimination of wire or other bottom racks or trays. 15

Although the upstanding arcuate portions or ribs are somewhat insulated against the direct action of the coils, these portions or ribs will become chilled by conduction from the flat portions of the plate, whether the ribs are formed into the 20 plate or are integrally united with the bottom sheet as by welding.

It is apparent that with my improved plate, the cold temperature or condition of the slab material is entirely transmitted to the outer plate 25 13 and radiated by the plurality of upstanding portions or ribs which, when meat is superposed thereon, provide a plurality of air circulating channels open at both ends to ensure free air flow. 30

By also embedding the elevated coil or pipe 10^a in a mass of conducting material, the case is given a greater "hold-over" period, after the refrigeration apparatus has been shut down, than heretofore has been the case. 35

At the same time frosting will be eliminated and hence a greater quantity of moisture in the case interior will be retained and hence the food-stuffs maintained in better condition.

Then, too, by providing the cold retaining slab 40 11^a and making it continuous with the bottom coil enclosing slab 11, the shifting of food-stuffs beneath the elevated coil 10^a is made impossible, while dripping of condensate onto food-stuffs or meat holding platters is obviated; hence a cleaner 45 and more sanitary condition of the display case obtained; at the same time providing more moisture in and less dehydration of the case contents; and the meat or food kept in better condition. 50

The invention has been described in terms employed merely for purposes of description and not as terms of limitation, as modifications may be made without, however, departing from the spirit of my invention as defined in the appended claims. 55

What I claim is:

1. In a display case of the character described provided with refrigerating coils in the bottom embedded in a downwardly sloping slab of temperature conducting and retaining compound, a temperature conducting metal plate intimately sealed to said slab, said plate being formed with upstanding food holding ribs arranged in parallel spaced relation to provide a plurality of sloping air circulating passages therebetween, said ribs terminating short of the longitudinal edges of 60 the plate and tapering into the main portion of the plate. 65

2. In a display case of the character described provided with refrigerating coils embedded in a downwardly sloping slab of temperature conducting and retaining compound, a temperature conducting metal plate intimately sealed to said slab, said plate being formed to provide a plurality of upstanding arcuate food holding portions spaced apart, said arcuate portions being arranged to pro- 70 75

vide a plurality of sloping open ended air conducting spaces.

3. In a display case of the character described provided with refrigerating coils arranged along the bottom and a refrigerating coil arranged above the normal bottom of the case, a slab composed of a mass of temperature conducting particles and binding material moulded about the

bottom coils and upwardly about the elevated coil in intimate relation with the coils, and an outer metallic covering for said slab intimately sealed by the binding material and formed with a plurality of upstanding portions spaced apart to provide air spaces therebetween. 5

ROLAND P. DAEMICKE.
